UNITED STATES PATENT OFFICE

2,469,148

INGOT MOLD CLEANER

George H. Bivens, Johnstown, Pa.

Application April 29, 1946, Serial No. 665,651

3 Claims. (Cl. 214—1)

1

This invention has reference, generally, to the cleaning of ingot molds and has for the primary object the provision of a device for handling ingot molds where the latter may be lifted from its stool, positioned at a selected side thereof, turned upside down to clean it of foreign accumulations, and then restored to its position on the stool in proper alignment with other molds thereon, with rapidity and ease and at a material saving in time, manpower, and operating costs.

In accordance with my invention a simple and effective ingot mold-engaging tool is provided for use with an open hearth furnace charging machine whereby the latter may be effectively employed in the performance of the operations above set forth.

The invention, together with the stated and other objects as may later become apparent, will be best understood from the following detailed description and accompanying drawing, in which:

Figure 1 is a side elevational view of a furnace charging device equipped with my invention and showing the tool engaged with the ingot mold;

Figure 2 is an enlarged fragmentary side elevation view for the purpose of showing to better advantage the application of my invention;

Figure 3 is an enlarged face view of the tool per se, with the charging bar of the charging machine shown in transverse section; and

Figure 4 is a longitudinal sectional view taken substantially on line 4—4 of Figure 3.

Having reference to the drawings, 5 indicates an ingot mold, one or more of which, and from which the ingots have been lifted or pulled, may be arranged on a stool 6, mounted on top of a car 7 which rolls along the rails 8. Before the molds 5 are again used for casting ingots it is desirable that they be cleaned of all foreign matter which may have accumulated therein.

My invention provides means for turning the molds upside down to facilitate removal therefrom of all foreign accumulations and then replace the mold in proper alignment on the stool 6 to be subsequently carried by the car or cars 7 into position to be charged or stored, or as otherwise determined upon. The customary practice of cleaning ingot molds is to manually turn them upside down to remove the residue therefrom. My invention contemplates the employment of an ordinary portable power driven type of open hearth furnace charging machine for furnishing mechanical energy as a means for turning the mold upside down to effect a cleaning and for replac-

2

ing the clean mold in its proper position on the car-supported stool.

In employing the charging device, indicated in the drawing by the numeral 9 the usual charging box or shovel arrangement is removed from the charging bar or peel 10, and a mold-engaging tool 11 is used in lieu thereof. As is well known in the art, the charging bar or peel 10 is capable of rotation in either direction, of reciprocatory movement, and also of moving upwardly and downwardly. The charging bar or peel 10 also includes a connecting pin or key 12 slidably mounted and actuated by a suitable mechanism of the charging apparatus.

15 The mold-engaging tool, constituting a salient feature of the present invention, consists of a pair of telescoping members 13, 14 that are adapted to be extended relative to one another for engaging the notched free end 15, 16 thereof with the lugs 17, 17a of the mold 5 at one side of the latter, and to be retracted for releasing the mold.

In the present instance, member 13 of the tool is secured to the free end of charging bar or peel 10 and braced with respect thereto by a suitable brace 18 as illustrated. Tool member 14 is adapted to be releasably secured at the desired position of adjustment with respect to the complementary tool member 13 by projecting the head end 19 of the connecting pin 12 into through opening 20, formed in member 13 and that opening 21 of a series of such openings formed in member 14 as might be brought into alignment with the aforementioned opening 20 (see Figs. 2 and 4).

35 Extension and retraction of tool member 14 is under control of the operator through the medium of a cable 22 that is trained over a pulley wheel 24 suitably journaled within a slot 25 provided in tool member 13 (see Fig. 4) and is secured at one end to the inner end of tool member 14 and at an opposite end to suitable mechanism of the charging apparatus.

In use, charging bar or peel 10 is thrust forward to place the tool members 13 and 14 in vertical alignment with the lugs 16 and 17 on one side of the mold 5. By slightly raising the bar 10 the notch 15 is engaged with the top lug 17 and by releasing tension on cable 22 tool member 14 will drop down to engage notch 16 with bottom lug 17a.

As openings 21 are so relatively spaced, having in mind the variations in the spacing of lugs 17, 17a as may exist in the various types and sizes of ingot molds, when the notched ends of the 55 tool members 13 and 14 are in positive engage-

ment with the lugs 17, 17a, one of the openings 21 will align with and intersect the through opening 20. The key or pin 12 is then thrust forward and the head 19 thereof engaged in the aligned openings to thereby detachably secure the mold to the charging bar or peel.

With the mold thus secured to the charging bar, power is applied to the latter for raising the mold off its platform 6, moving the mold to one side of the car 7, turning the mold upside down to permit the desired cleaning thereof, righting the mold, and then returning the mold to its proper position on the platform, all in the order stated.

After the cleaned mold has been restored to its proper place, pin 12 is retracted to free tool member 14 so that upon proper manipulation of cable 22 and bar 10 the tool members are readily disengaged from lugs 17, 17a and the parts are then in position for repeating the cycle of operation just described for effecting and cleaning of the next succeeding mold 5.

It will be appreciated from the foregoing that with a device as contemplated by this invention the cleaning of molds by the desirable process of turning the mold upside down will be accomplished with rapidity and ease and with material saving in time, manpower, and operating cost.

It is understood that while I have herein described a preferred embodiment of my invention, nevertheless various changes may be made therein, within the scope of the claims hereto appended.

What I claim is:

1. Apparatus for handling ingot molds of the type having lugs arranged in pairs on opposite sides thereof, comprising a tool embodying a pair of members slidably relative to one another and respectively having one end thereof adapted to engage a lug of the mold, one of said tool members being positively secured to the free end of the charging bar of a furnace charging machine, and said members being complementarily equipped to be engaged by the connecting pin slidably carried by the charging bar to be secured thereby at the desired position of adjustment relative to one another.

5 2. A mold handling apparatus comprising in combination with an open hearth furnace charging machine having a charging bar and a connecting pin slidably mounted thereon, of a two-part tool having its parts relatively longitudinally adjustable on the free end of the charging bar and having notched terminals adapted to be moved into and out of engagement with the lugs at one side of the ingot mold, and also having means cooperable with the connecting pin for securing the tool at a selected position of longitudinal adjustment, and means connected with the tool for controlling adjustment of the tool.

10 15 3. A tool for releasably securing an ingot mold to the charging bar of an open hearth furnace charging machine, comprising a pair of telescoping members each of which has a free end provided with a notch to engage a lug on the ingot mold, one of said members being adapted to be mounted on the free end of a charging bar of the charging machine and provided with a through opening, and the other of said members having a series of openings adapted for registry with the opening in the first member to receive the free end of the connecting pin carried by the charging bar to releasably secure the tool members in various positions of adjustment relative to one another, and said other tool member being also provided with means for controlling telescopic movement thereof.

30 GEORGE H. BIVENS.
